ATLANTA.

UNITED STATES PATENT OFFICE.

HENRY BUSH SPENCER, OF OTTAWA, ONTARIO, CANADA.

TRAIN STOP AND TRAIN CONTROL.

1,414,596.

Specification of Letters Patent. Patented May 2, 1922.

Application filed December 27, 1921. Serial No. 524,992.

To all whom it may concern:

Be it known that I, HENRY BUSH SPENCER, a subject of the King of Great Britain, and resident of the city of Ottawa, in the Province of Ontario and Dominion of Canada, have invented certain new and useful Improvements in Train Stops and Train Control, of which the following is a specification.

10 This invention relates to improvements in train stops, and particularly to that class of device in which the train is automatically stopped by the application of the air brakes should it overrun a warning torpedo placed 15 on the track, and the objects of the invention are to enable the train after being stopped to proceed slowly on its way without the necessity of the engineer leaving his cab to reset the train stopping device.

20 Further objects are to provide a simple and effective device of this character which will cause the stopping of a train should the engine be derailed from any cause whatever, whereby the train will be brought to a stop 25 before there is any loss of life or heavy damage done to equipment, track or road-bed, the operation of the device being such that the engine and train will, in all probability, be brought to a stop while in upright 30 position and before overturning, the brakes being automatically applied much quicker than they could be applied by the engineer through the operation of the engineer's valve if he had any opportunity to 35 reach and operate the same.

Further objects of the invention are generally to improve and simplify the construction of the device to enable the various parts to better perform the functions required of them.

And it consists essentially of the improved construction hereinafter described in detail in the accompanying specifications and drawings.

40 In the drawings:

Figure 1 is an elevation of an embodiment of the invention applied to a locomotive, which latter is shown in part in dotted lines.

Figure 2 is an elevation, illustrating the 50 operation of the device upon explosion of the torpedo.

Figure 3 is a perspective view of the signalling element.

Figure 4 is a side elevation of the signalling element.

Figure 5 is a sectional view through the same.

Figure 6 is a front elevation.

Figure 7 is a sectional detail, showing the supporting means for the frangible element. 60

In the drawings, like characters of reference indicate corresponding parts in all the figures.

Referring to the drawings:

A represents a locomotive of any usual 65 construction well known in the art, and B represents an extension of the ordinary well-known brake pipe line; C, the engineer's brake valve; D, an air gauge of any convenient type; E, a cut-out cock or valve; 70 and F, the signalling element. The signalling element is connected to the gauge D by a connecting conduit or pipe G which, within the engineer's cabin, is connected to T-coupling 10 from which a branch pipe 11 75 extends to the cock E, the opposite side of the cock being connected to a T-coupling 12 in the train line pipe B which is connected to the engineer's valve C.

The signalling device F comprises a tubular member 13 having its outer periphery stepped and formed with a shoulder 14 adapted to abut a supporting bracket 15 secured to the front of the locomotive. The outer extremity of the tubular member F is 85 screw-threaded at 16 to receive an internally screw-threaded coupling 17 which connects with the threaded end of the pipe G.

The opposite end of the sleeve 13 to that formed with the threading 16 is provided 90 with an enlarged head 18 externally screw-threaded and having a cap 19 internally screw-threaded and engaged with the threading thereon, the cap being formed with an inwardly-turned annular flange 21 which 95 retains the frangible member 22 in position, said member being conveniently formed of a glass disc having resilient packing rings 23 and 24 of rubber or the like on opposite sides thereof and held between the flange 21 and the face of the head 18, respectively. The glass is thus provided with an air-tight joint.

In order to prevent injury to the packing ring 24, a thin metallic ring or washer 25 105 may be provided between it and the face of the head 18. The frangible member 22 is angularly disposed in front of the locomotive and located in close proximity to the front wheel and to the ball of the rail, and 110

may be connected to the bracket by a suitable clamp 26 connected by bolts 27 to the brackets. The connecting pipe G may be also provided at intervals with clips 28 by which it is attached to the locomotive.

In railway practice it is common to use torpedoes on the railway track, and this improved train stop is utilized in conjunction with these torpedoes. When a torpedo is placed upon a rail by a trackman, or other person, for the object of warning an approaching train, it often happens that the signal is not heard or is disregarded. Such a torpedo H is shown on the track in Figure 1, and, if a locomotive equipped with this improved train stopping device approaches and passes over the torpedo H, then the torpedo is exploded and the concussion shatters the glass 22, allowing the air to escape from the pipe G, which allows the air to escape from the train line pipe B connected therewith through the conduit 11, the valve E being in such position that this conduit is opened. This will at once bring the train to a standstill, and the engineer may thereupon turn the cock E which will close the train line pipe and permit the train to proceed, but, having been warned by the breaking of the frangible member, he will only proceed at slow speed until the next station, when the frangible glass disc 22 may be replaced.

The gauge D indicates when pressure is maintained within the pipe G, and, when the device is in normal condition, the gauge will show pressure. When the cock E is turned after operation of the warning signal, no pressure will remain in the conduit G, and consequently nothing will be indicated on the gauge D, and this will constitute a warning to the engineer that his signal is not in operative condition and will remind him in case it should be overlooked.

It will be observed that it is possible for the engineer to close the conduit G and proceed on his way without leaving the engine cab.

Both sides of the locomotive and the tender will, if necessary, be equipped with the train stop, so that, in the event of a locomotive being turned on a turn table or

used for backing up purposes or any other function in railway practice, the train stop will always be available or operative.

After the flagman places a torpedo on the rail, he will take up his position the proper distance from the torpedo, flag or fuses, as per regulations, and when he has the train under control, he may remove the torpedo and give the usual hand proceed caution signal until he can converse with the engineer and explain to him why the train has been stopped. On the other hand, if the engineer fails to recognize the flagman's signal and passes the flagman, then the torpedo will stop him in the manner above described and thereby prevent a rear end or other accident.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

A train stopping device comprising, in combination, an engineer's brake valve, a brake line pipe, a T-coupling connected to the brake line pipe, a connecting conduit connected to the T-coupling, a valve in the connecting conduit, a second T-coupling connected on the opposite side of the valve to the first-mentioned T-coupling, an air gauge connected to one side of the second T-coupling, a conduit connected to the opposite side of the second T-coupling, a frangible signalling device connected to said last-mentioned conduit and located in close proximity to the rail and adapted to be broken by the exploding of a torpedo, all as substantially herein set forth and described.

In witness whereof I have hereunto set my hand in the presence of a witness.

HENRY BUSH SPENCER.

Witness:

RUSSEL S. SMART.
